ACCOUNTING MACHINE

Lurelle V. A. Guild, New York, N. Y., assignor to
Underwood Corporation, New York, N. Y., a
corporation of Delaware

Application December 28, 1950, Serial No. 13,614

Term of patent 14 years

(Cl. D64—11)

To all whom it may concern:

Be it known that I, Lurelle V. A. Guild, a citizen of the United States, residing in New York, county of New York, and State of New York, have invented a new, original, and ornamental Design for an Accounting Machine, of which the following is a specification, reference being had to the accompanying drawing, forming a part thereof.

In the drawing:

Fig. 1 is a front perspective view of the accounting machine, and

Fig. 2 is a rear perspective view thereof.

The essential features of my design for an accounting machine reside in the parts shown in full lines.

What is claimed is:

The ornamental design for an accounting machine, substantially as shown and described.

LURELLE V. A. GUILD.
